UNITED STATES PATENT OFFICE.

GOTTFRIED M. LIEB, OF NEWARK, ASSIGNOR TO DANIEL A. BEAM, OF BLOOMFIELD, NEW JERSEY.

DESIGN FOR A JEWELRY-CHAIN.

SPECIFICATION forming part of Design No. 12,595, dated December 13, 1881.

Application filed November 7, 1881. Term of patent 14 years.

To all whom it may concern:

Be it known that I, GOTTFRIED M. LIEB, of Newark, in the county of Essex and State of New Jersey, have originated and produced a new and Improved Design for Jewelry-Chains, 5 of which the following is a specification.

In the accompanying drawings, which is upon a greatly-enlarged scale for the sake of clearness, Figure 1 represents a side view of a piece 10 of chain embodying my design. Fig. 2 is a similar view taken at right angles to Fig. 1. Fig. 3 represents a face view of a single link detached, and Fig. 4 represents an edge view of the link. Only one form of link is used in making this chain, and the shape of the link is 15 clearly shown in Fig. 3.

The link A is flat or disk-like in form, and has a circular profile and a central circular opening, *a*, from which a narrow cleft, *b*, extends 20 to the outer profile or circumference, the sides of the cleft being divergent from each other from the opening *a* outward. Upon opposite sides of the opening *a* and cleft *b* are straight slots *c*, which converge toward the cleft, as 25 clearly seen. In the chain these links are arranged in pairs, and I have designated the links of alternate pairs by the letter A and the links of intermediate pairs by the letter B.

In making the chain I commence at what is 30 here the lower end of the chain, and pass two links, B B, of the second pair through the slots

c c in the links A A of the first pair. The links A A of the third pair I pass through the slots *c c* in the links B B of the second pair, and the links B B of the fourth pair I pass through the 35 slots *c c* in the links A A of the third pair, and so on until the required length of chain is obtained.

It will be seen that the links A A or B B of each pair stand at an angle to each other, or 40 converge, as clearly seen in both Figs. 1 and 2, and the links A A of alternate pairs stand at right angles to the links B B of intermediate pairs, thus forming chain which is of approximately-square cross-section. 45

What I claim, and desire to secure by Letters Patent, is—

1. The design for a chain-link herein shown and described, consisting of a circular disk with the central opening, *a*, the cleft *b*, and the converging slots *c*. 50

2. The design for a chain, consisting of the circular links having central openings, *a*, clefts *b*, and converging slots *c*, said links being arranged in pairs, and the links of alternate pairs 55 being at right angles to the links of intermediate pairs, as herein shown and described.

GOTTFRIED M. LIEB.
